WRITING INSTRUMENT

Homer Theodore Green, Milton, Wis., assignor to The Parker Pen Company, Janesville, Wis., a corporation of Wisconsin

Filed Nov. 2, 1959, Ser. No. 58,151

Term of patent 14 years

(Cl. D74—17)

Fig. 2 is a front elevational view thereof;

Fig. 3 is a rear elevational view thereof; and

Fig. 4 is a bottom plan view thereof on larger scale.

The essential features of the design reside in the portions shown in solid lines on the drawing.

I claim:

The ornamental design for a writing instrument, as shown and described.
